UNITED STATES PATENT OFFICE.

RICHARD VARLEY, OF ENGLEWOOD, NEW JERSEY.

ELECTRICAL SYSTEM.

1,103,385.

Specification of Letters Patent. Patented July 14, 1914.

Original application filed June 16, 1913, Serial No. 773,807. Divided and this application filed March 21, 1914. Serial No. 826,235.

To all whom it may concern:

Be it known that I, RICHARD VARLEY, a citizen of the United States of America, residing at Englewood, in the county of Bergen and State of New Jersey, have invented new and useful Improvements in Electrical Systems, of which the following is a full, clear, and exact description, reference being had to the accompanying drawings, which

10 form part of this specification.

This invention relates to systems for producing electrical discharges from a source of energy. As such a device I provide means for causing a high tension effectively sustained discharge of current without employment of large and heavy apparatus and which may find embodiment in many systems, such as wireless telegraphy, and ignition systems for exploding the charge of

20 internal combustion engines.

The broad feature, herein disclosed, of building up a supernormal state of flux for prolonged energizing of a current using instrumentality is covered by Patent No. 25 1,081,413, granted to me December 16th, 1913, and to divisional subject matter of which the present application is directed.

In the accompanying drawings herein-after described, I have illustrated my invention as embodied in an ignition system for internal combustion engines but it will be premised that I do not desire to limit myself thereto, said embodiment being only one of the many uses of which my invention

35 is capable.

The usual ignition system employing a coil or generator inductively wound produces a high voltage spark of short duration and low heat, and therefore, poor ignitive value. This is due to the radical magnetizing and demagnetizing effect upon the core or armature of the inductive generator, upon breaking of the primary circuit, and resultant non-sustained magnetic flux action; the 40 momentarily induced current in the secondary winding producing a correspondingly short ineffective spark, and while in the alternating current high tension magneto or generator there is a certain amount of current augmentatively generatively impressed upon the secondary winding of the armature, by reason of its rotation, after the 45 primary circuit has been interrupted, the

amperage is so slight that it is practically 55 impotent. It is also commonly known that in the usual ignition systems, self-induction and reactance in the interrupted primary winding, causes flashing or sparking at the interrupter contacts, which necessitates the employment of the more expensive, precious 60 and less readily oxidizable metals, such as platinum, and iridium for contact service, and also requires a condenser or other spark 65 arresting means connected across said contacts, for the absorption of such extra or self-induced current, as a protection to the contacts.

By my invention there may be readily 70 formed a spark having the character substantially of arc-sustenance and high heat 75 value as contra-distinguished from the instantaneously delivered low heat spark above referred to, thereby producing a spark operatively alive for a greater period of time relatively to the travel of the piston, than 75 heretofore has been possible and thus making it effective upon thin or weak gas mixtures and such charges as contain occluded dead or weak spots. Furthermore, I provide 80 a system in which I may dispense with the condenser or other spark arresting means.

My invention comprises, broadly stated, the combination with a source of current, of 85 transformer means and mechanism for effecting energizing of and for controlling the transformer with respect to the source of current to cause operative sustained energizing of a current using instrumentality, as 90 prolonged bridging of the gap of a spark plug, as will be hereinafter more fully described.

Figure 1 is a diagrammatic view of circuits and apparatus showing my invention as employed in connection with an ignition system, said diagram showing a generator 95 as a source of current; and Fig. 2 is a similar view showing switch and circuit connections for effecting energizing of the transformer from a source of alternating current or a source of continuous or direct 100 current, such as a battery.

In Fig. 1 I show a magneto generator of the high frequency type, the same being one of the many types of inductive generator for ignition service on autovehicles. How- 105 ever, I do not desire to limit my invention

to the employment of any particular type of generator or means affording a source of current, as my device is advantageously operable with any type of generator or with a battery or accumulator, as the source of energy. This alternating current generator, which indicated by the numeral 2, (preferably being of the standard type for a four cylinder four cycle engine) has its ignition energizing circuit or inductive winding grounded at one end, as at 3, while the other end connects through a switch 4 to winding of transformer mechanism 5 forming part of the spark producing apparatus shown. The transformer device comprises a core 6 which may be of any suitable shape or construction and which carries on the legs 7 and 8 thereof windings 9 and 10 respectively, both of which are grounded, as at 11, to bring them in circuit with the generator through ground 3. In the circuit of the winding 10 is interrupter mechanism 12 which may be of any suitable construction and comprises essentially a fixed contact 13, a movable contact 14 in the form of a contact lever, and a contact actuating cam 15; the contact 13 and lever 14 preferably being insulated. Also arranged upon the legs 7 and 8 of the transformer core 6 are secondary windings 30 *a* and *b* preferably serially connected, one end leading to ground 11 and the other end connecting with a rotating contact arm 16 of distributor mechanism 17 of spark producing apparatus, the segmental contacts 18 of which distributor connect with the usual spark plugs 19 of an engine (not shown) that are grounded at 20, as through the cylinders of the engine. Proper synchronizing of the distributor with the circuit interrupting mechanism may be effected in any suitable manner, the interrupter cam 15 being of such construction and so arranged as to cause symmetrically periodic or commensurate closing and opening of the circuit of the coil or winding 10, at a suitable point or points in the alternating current wave, as hereinafter described. It will be understood that the generator 2 may be driven by the engine through any suitable form of connection or gearing (not shown) so as to energize the coils of windings 9 and 10. The circuit of the winding 10 is normally closed by the interrupter mechanism 12, therefore energizing of the windings 9 and 10 by the generator induces a magnetic flux in the transformer core 6, which seeks the normal magnetic path of the core. The turns of winding of these coils 9 and 10 are unidirectionally wound with the result that the lines of force set up respectively by these two coils tend to meet one another in opposition at an intermediate point in the core, causing them to take an abnormal path. The abnormal path taken is preferably a magnetically reluctant one, as by employing

a core, such as shown, in which the flux, upon saturation of the core, takes a leakage path across an air gap or space intermediate the sides of the transformer. Rotation of the cam 15 of the interrupter mechanism, causes sudden opening of the circuit of the coil or winding 10 preferably at a suitable point in the alternating current wave. This point of opening of the circuit may take place, by reason of synchronous relationship of the cam and phases of the generator, at or near the peak or maximum point or period of flow of the current wave. Opening of the circuit of the winding 10 causes a violent change of flux in the leg 8 and the diverted or repressed flux takes the less resistant or normal path provided by the core, setting a magnetic surge in the core of great intensity, particularly through the leg 8. Inasmuch as the circuit of the winding 9 is not broken by the interrupter but remains in energizing relationship with the generator, the rate of change of flux in the leg 7 is not so great as that in the leg 8, upon opening of the circuit of the winding 10, but, with said windings 9 and 10 connected in parallel with the generator operating at normal full load, opening of the circuit of the winding 10 causes a rise in voltage in the winding 9. As a result of said flux change and magnetic surge, the voltage is immediately generatively built up to an intense degree in the secondary coils or windings *a* and *b* of the transformer, breaking down or bridging the air gap between the electrodes or terminals of the respective spark plug connected in circuit through the distributor mechanism above described. The spark thus formed is not a mere instantaneous flash or of brief duration. It continues to burn substantially in the form of a flaming arc maintained by a resident body of flux in the core, for the breaking down of the normal reluctance of the spark gap and inauguration of the spark or arc in effect causes a closing of the circuit containing the secondary coil of the windings, with the result that there is established a mutual or reciprocal regulative relationship between the arc and secondary winding or flow of flux which tends to prevent immediate equalization of the flux or demagnetization or dissipation of the energy of the transformer, the arc assuming a rheostatic function and causing the windings *a* and *b* to substantially choke or strain the large body of flux in such manner as to prolong its activity with respect to arc or flame maintenance at the plug. Furthermore, the winding 9 continues to supply energy at a slight increase in voltage, to the core 6 and to generatively impress a current, in the particular arrangement shown, upon the secondary coil or winding *a*, assistive or additive to the normal current in the sec-

ondary winding set up or induced by the flux in the transformer core. A spark of the above character, that is, sustained in an arc-like manner, is highly effective upon thin or weak gas mixtures or such charges as are of low volatility. Where the system is employed in connection with other apparatus in which it is desired to effect sustained energizing of the current using instrument thereof, as in the case of wireless telegraphy, it will be found of great value. Instantaneous establishment of the spark at the plug or other current using instrument and its maintained utilization of energy causes the active secondary circuit containing the spark producing means, to so absorb the energy and control the flux action as to prevent self-inductance of a sparking current in the circuit containing the interrupter contacts. As a result, there is little or no tendency to sparking between the interrupter contacts upon opening of the circuit of the coil 10. I am thus enabled to employ ordinary material, such as copper, for the above parts, and dispense with the use of a condenser or other spark arresting means which is necessary in the ordinary systems to absorb the sparking resulting from interruption of a primary circuit. However, I do not desire to limit my invention to a system in which no condenser is employed for a condenser may be necessary where abnormal conditions obtain in the circuits. I have, therefore, indicated in dotted lines, such a condenser 21 connected across the interrupter contacts.

In Fig. 2 I have shown a modified form of my invention wherein means are provided for setting up energizing of the transformer through a separate source of energy such as a battery; the arrangement being desirable in that it affords means for providing an effective ignition current prior to such times as the generator 2 may furnish a current of proper voltage or at such times when it is desired to run on battery ignition independently of the generator 2. In this view I show a system corresponding with that disclosed in Fig. 1 with the exception that circuit and switch means are provided for setting up from a battery circuit, inductive energizing of the secondary windings *a* and *b* of the transformer, as by a battery 22. The transformer windings remain the same but a double arm switch arrangement 23 is provided to bring the windings 9 and 10 into circuit with the generator 2 or the battery 22. When the double arm switch is shifted to contacts 24 and 25, current flows from the generator to switch arm 4', winding 9 and, with the interrupter mechanism closed, through winding 10, and then to ground 11 back to the generator through ground 3. More particularly current flows through lead 26 and then divides at 27 and

flows in parallel through lead 28 and switch arm 4^b to coil 9, and through interrupter mechanism 12 to coil 10; the flux building up in the transformer pending opening of the circuit of the winding 10 and resultant discharge of current in the secondary windings *a* and *b*, as already described in connection with Fig. 1. When the double arm switch is shifted to contacts 29 and 30, the generator circuit above described, for energizing the transformer windings, is broken and current flows from the battery through lead 26 and interrupter mechanism 12 and thence through coil 10 and in parallel through coil 9 via lead 31 and switch arm 4^b to grounds 11 and 32, back to battery; the interrupter mechanism 12 being common to the circuits of both coils or windings 9 and 10. The battery current induces a flux which, by reason of the unidirectional arrangement of the coils or windings 9 and 10, tends to seek an intermediate abnormal path as in the case of the alternating flux described in connection with Fig. 1 and the alternating current circuit connections described above in connection with the present Fig. 2. Opening of the interrupter mechanism causes the flux to take the normal path provided by the core, with the result that the change of path of travel and surge of the flux induces a high potential current in the secondary windings *a* and *b*, which is sustained by the tendency of the arc closed circuit of the secondary winding or coils, to restrict immediate exhaustion of the flux, in the manner set forth in the description of the arrangement shown in Fig. 1. Where my system is employed in connection with a high frequency generator, such as indicated, the gage or size of the turns of the windings 9 and 10 of the transformer would be preferably such as to present no resistance impeding to effective flow of the high frequency current therethrough. The result is that such windings would not present a desired resistance to the direct or continuous current flow of the battery. To overcome any such dissipating capacity effect upon the battery, I may insert a resistance in the battery circuit. This resistance is indicated by the numeral 33 and may be of any suitable character, the same being commonly connected to or in series-parallel relationship with the transformer windings 9 and 10 when the battery circuit connections, above described, are made, and being out of circuit with said windings when the generator connections are made, through the double armed switch arrangement 23. In Fig. 2 I have also indicated the condenser 21 connected across the interrupter contacts. As stated above, I do not desire to limit myself with respect to condenser connections as the condenser may prove necessary under certain conditions and can be used in the

battery circuit to absorb any sparking that may result from interrupting both of the windings 9 and 10.

The advantages of my invention will be found to reside in a system whereby prolonged energizing of a current using instrumentality is obtained by the use of simple, small and compact apparatus and through the employment of either alternating or continuous current. My system operates to instantaneously break down the resistance of the spark gap with a current of high voltage and to follow the initial formation of the spark with a current of sustained high heat value. In both cases, *i. e.*, either in the use of alternating current or continuous or battery current, this arc-like sustained spark obtains, said flame being highly effective upon gas charges which can not be exploded by the usual momentarily delivered spark or flash common to ignition systems as heretofore used.

Many changes may be made in the arrangement shown and described. The circuit and switch connections may be changed without departing from the principle of energizing and controlling the transformer, and it will also be apparent that any suitable form of generator may be employed for energizing the transformer.

Having thus described my invention, what I claim and desire to secure by Letters Patent is:

1. A source of energy and a circuit therefor, a plurality of coils inductively related thereto, a current using instrumentality in circuit with one of said coils, and means for bringing another of said coils into circuit with said source.
2. A source of energy and a circuit therefor, a primary coil inductively related to said circuit, and a plurality of secondary coils inductively related to said primary coil.
3. A source of energy and a circuit therefor, a primary coil inductively related to said circuit, and a plurality of secondary coils inductively related to said circuit and the primary coil.
4. A source of energy and a circuit therefor, a primary coil inductively related to said circuit and having in circuit controlling means, and a plurality of secondary coils inductively related to said primary coil.
5. A source of energy and a circuit therefor, a primary coil inductively related to said circuit and having in circuit controlling means, and a plurality of secondary coils inductively related to said first named circuit and the primary coil.
6. A source of energy and a circuit therefor, a plurality of coils inductively related thereto, a current using instrumentality in circuit with one of said coils, and make-and-

break mechanism for bringing another of said coils into and out of circuit with said source.

7. A source of energy and a circuit therefor, a primary coil inductively related to said circuit, a secondary coil inductively related to said primary coil, and circuit controlling mechanism for said first named circuit and the primary coil.

8. A source of energy and a circuit therefor, a primary coil inductively related to said circuit, controlling mechanism for said circuit and the primary coil, and a secondary coil inductively related to said circuit and the primary coil.

9. A source of energy and a circuit therefor, a primary coil inductively related to said circuit, controlling mechanism for said circuit and the primary coil, and a plurality of secondary coils inductively associated with said circuit and the primary coil.

10. A source of energy and a circuit therefor, a primary coil inductively related to said circuit, and a secondary circuit comprising a plurality of coils inductively related to said first named circuit and the primary coil.

11. A source of energy and a circuit therefor, a primary coil inductively related to said circuit, interrupter mechanism in said circuit, a secondary coil inductively related to said primary coil, and a current using instrumentality connected in circuit with said secondary coil.

12. A source of energy and a circuit therefor, a primary coil inductively related to said circuit, interrupter mechanism connected in said circuit, and a secondary coil inductively related to said circuit and the primary coil and having in circuit a spark gap.

13. A source of energy and a circuit therefor, a primary coil inductively related to said circuit, and a secondary circuit comprising a plurality of coils one of which is inductively related to said first named circuit and another of which is inductively related to the said primary coil.

14. A source of energy and a circuit therefor, a primary coil inductively related to said circuit, and a secondary circuit comprising a plurality of coils one of which is inductively related to the first named circuit and another of which is inductively related to the said circuit and the said primary coil.

15. A source of energy and a circuit therefor, a primary coil inductively related to said circuit, and a secondary circuit comprising a plurality of serially connected coils inductively related to said circuit and the primary coil.

16. A source of energy, a coil connected in circuit therewith, a primary coil inductively related to said first coil, controlling mecha-

- nism in circuit with said first coil, and a secondary coil inductively related to said first coil.
17. A source of energy, a coil connected in circuit therewith, a primary coil inductively related to said first coil, controlling mechanism in circuit with said first coil and the primary coil, and a secondary coil inductively related to said first coil.
18. A source of energy, a coil connected in circuit therewith, a primary coil inductively related to said first coil, controlling mechanism in circuit with said first coil and the primary coil, and a secondary coil inductively related to said first coil.
19. A source of energy and a circuit therefor, three or more coils inductively related to said circuit and to one another, and controlling mechanism connected in circuit with two or more of said coils.
20. A source of energy and a circuit therefor, three or more coils inductively related to said circuit and one of which has in circuit a spark gap, and controlling mechanism in circuit with another of said coils.
21. A source of energy and a circuit therefor, three or more coils inductively related to said circuit and one of which has in circuit a spark gap, and controlling mechanism in circuit with one or more of said coils.
22. A source of energy, a transformer core, a plurality of coils adapted for connection with said source and so arranged with respect to the core as to set up in the latter opposing lines of magnetic flux, secondary winding inductively related to one of said coils, and means for bringing one of the first named coils into and out of connection with the source of energy.
23. A source of energy, a transformer core, a plurality of coils adapted for connection with said source and so arranged on the core as to set up a magnetic flux therein, secondary winding inductively related to one of said coils, and means for intermittently bringing one of the first named coils into such connection with the source of energy as to set up a magnetic flux in opposition to lines of force set up in said core by another of said first named coils.
24. A source of energy, a transformer core, a plurality of coils adapted for connection with said source and so arranged with respect to the core as to set up in the latter opposing lines of magnetic flux, secondary winding inductively related to said coils, and means for bringing all of said coils into and out of connection with the source of energy.
25. A source of energy, a transformer core, a plurality of primary windings adapted for connection with said source and so arranged on the core as to set up opposing lines of magnetic flux therein, secondary winding inductively related to said primary windings, and means for bringing said primary windings into and out of connection with said source of energy.
26. A transformer core, means for setting up therein a magnetic flux and causing said flux to take a leakage path and comprising a plurality of windings adapted for connection with a source of energy, and secondary winding inductively related to said core.
27. A transformer core, means for setting up therein a magnetic flux and causing said flux to take a leakage path and comprising a plurality of windings one of which is connected with a source of energy and means for bringing another of said windings into and out of connection with said source of energy, and secondary winding inductively related to said core.
28. A transformer core having a closed magnetic circuit, a plurality of primary windings the turns of which are unidirectionally wound on said core and adapted for connection with a source of energy, secondary winding inductively related to one of said primary windings, and make and break mechanism for controlling one or all of said primary windings with respect to inductive relationship with said core.
29. A transformer core having a closed magnetic circuit, a plurality of primary windings unidirectionally wound upon said core, means for connecting said windings in parallel with a source of energy, and secondary winding inductively related to said winding.
30. A plurality of primary windings inductively related to one another, means for alternately connecting said windings with a source of alternating current and direct current, and secondary winding inductively related to said primary windings.
31. A plurality of primary windings inductively related to one another unidirectionally wound upon a transformer core, means for alternately connecting said windings with a source of alternating current and direct current, and secondary winding inductively related to said primary windings.
32. A plurality of primary windings, circuit controlling mechanism, and means for connecting all of said windings to a source of alternating current and one of said windings in circuit with the controlling mechanism and for bringing said windings out of alternating current connection and into connection with a source of continuous current and with said controlling mechanism.
33. A source of alternating current, a source of continuous current, a plurality of coils inductively associated with one another, switch means for connecting said coils in circuit with either one of said sources, secondary winding inductively re-

6
lated to said coils, and interrupter mechanism for bringing one of said coils intermittently out of circuit with said source of alternating current and for bringing all of 5 said coils intermittently out of circuit when said coils are connected in continuous current circuit.

34. A transformer core, a plurality of coils arranged thereon, secondary winding 10 inductively related thereto, circuit controlling mechanism, and means for connecting all of said windings in parallel with a source of alternating current, and for bringing said windings out of alternating current connection and into energizing relationship with a source of continuous current and into circuit with the controlling mechanism;
- 15 35. A plurality of primary windings, a

source of alternating current, a source of 20 continuous current, secondary winding, interrupter mechanism, and switch means for connecting said primary windings in circuit with the source of alternating current and one of said primary windings into circuit with the interrupter mechanism, and for bringing said primary windings out of 25 alternating current connection and into parallel connection with a source of continuous current and in circuit with the interrupter mechanism.

In testimony whereof I have hereunto set my hand.

RICHARD VARLEY.
